ION VON KERT HOTT, OF DAYTON, OHIO, ASSIGNOR TO THE JOYCE-CRIDLAND COMPANY, OF DAYTON, OHIO, A CORPORATION OF OHIO

LIFTING MECHANISM

Application filed December 17, 1928. Serial No. 326,423.

This invention relates to a lifting mechanism and more particularly to a mechanism for elevating an automobile to permit access to be had to the chassis for the purpose of lubricating the same.

One object of the invention is to provide a hydraulic lifting mechanism which will be simple in its construction, efficient in operation and which can be easily controlled.

A further object of the invention is to provide such a mechanism with controlling means of such a character as to safeguard the mechanism against accidental release.

A further object of the invention is to provide a hydraulic mechanism in which the lifting element will be actuated by a liquid under air pressure; and to provide means whereby the air which has been used to actuate the lifting mechanism can be used for other purposes without releasing the load.

A further object of the invention is to provide such a lifting mechanism with runways having at their ends pivoted parts which may be placed either in an inclined position to guide the automobile onto the runways or may be locked in elevated positions to serve as stops.

A further object of the invention is to provide means for supporting the runways with their lateral edges spaced above the supporting surface to prevent injury to the operator in the event his foot should be partially beneath one of the runways when the load is lowered.

Other objects of the invention will appear as the mechanism is described in detail.

In the accompanying drawings Fig. 1 is a plan view of a lifting mechanism embodying my invention and partly broken away; Fig. 2 is a vertical sectional view taken on the line 2—2 of Fig. 1 centrally through the mechanism with the runways partly broken away; Fig. 3 is a transverse section taken on the line 3—3 of Fig. 2; Fig. 4 is a sectional detail view of the controlling valve; Fig. 5 is a sectional detail view of the check valve for the air line; Fig. 6 is a side elevation of the end portion of one of the runways showing the pivoted member or shoe in its lowered position; Fig. 7 is a similar view showing the pivoted member locked in an elevated position; Fig. 8 is a transverse sectional view of one of the runways taken on the line 8—8 of Fig. 1.

ing the pivoted member locked in an elevated position; Fig. 8 is a transverse sectional view of one of the runways taken on the line 8—8 of Fig. 1.

In these drawings I have illustrated one embodiment of my invention but it will be understood that this has been chosen for the purpose of illustration only, and that the mechanism may take various forms and may be used for various purposes without departing from the spirit of the invention.

In that particular embodiment of the invention here illustrated the lifting mechanism as a whole comprises a cylinder 10 which preferably is embedded in the ground with its upper end adjacent to the surface of the ground. Mounted within the cylinder 10 for vertical movement with relation thereto is a plunger or piston 11 with which is connected the load supporting device. As here shown, the plunger is cylindrical in form and is of such length that when in its lowermost position the upper end thereof will project above the cylinder. Rigidly secured to the projecting upper end of the plunger is a casting 12 to which is rigidly secured a transverse frame member 13 which, in the present instance, is in the form of a channel bar. Mounted on this transverse frame member, near the respective ends thereof, are runways or tracks 14 adapted to support the wheels of an automobile and preferably provided with upright flanges 15 to retain the wheels against lateral displacement with relation to the runways.

The plunger 11 is hollow and is closed at its lower end by a head 16 and at its upper end by a head 17. Both the cylinder and the plunger are adapted to contain a liquid, preferably oil, and when the plunger is in its lowermost position it will be filled with liquid to a point spaced a short distance from the upper head 17. The upper end of the cylinder is tightly closed and, in the present instance, a bearing member 18 is rigidly secured to and arranged within the upper end of the cylinder to receive the plunger. This bearing member is provided with a packing gland 19 to seal the connection between the same and the plunger. The

bearing member has a downwardly extending portion 20 engaging the plunger some distance below the top of the cylinder and provided an elongated bearing which will brace the plunger against lateral strains and 5 which will be engaged by a stop or flange 21 at the lower end of the plunger to limit the upward movement of the plunger.

The interior of the plunger is connected with the cylinder by a suitable conduit so 10 that the liquid may be forced from the plunger through this conduit and into the cylinder where it will act upon the lower end of the plunger to elevate the latter. The conduit may take various forms but it is 15 preferably carried by the plunger and, in the present construction, comprises a pipe 22 extending through the upper head 17 of the plunger to a point near the bottom of the plunger where it has open communication 20 with the interior thereof. A packing gland 23 seals the joint between the pipe and the head 17. A second pipe 24 extends through the upper head 17 of the plunger, where it is 25 provided with a packing gland 23a, through the full length of the plunger and through the lower head 16 thereof, so that it has open communication with the cylinder beneath the plunger. The upper or outer ends of the 30 two pipes 22 and 24 are connected one to the other and means are provided for controlling the flow of liquid therethrough. In order that the controlling means may be located for convenient operation I have connected the upper end of the pipe 22 with a 35 laterally extending pipe 25 and have connected the upper end of the pipe 24 with a laterally extending pipe 26. These pipes 25 and 26 are substantially parallel and extend 40 transversely to the plunger to a point beyond one of the runways 14 where the ends of the pipes 25 and 26 are connected one with the other, this connection preferably comprising a valve 27. The valve 27 is of such 45 a character that normally it will operate to permit the liquid to pass from the pipe 25 of the conduit to the pipe 26 thereof and to prevent the passage of the liquid in a reverse direction. Manually operated means are 50 provided for opening the valve to permit the liquid to flow in a reverse direction, that is, to pass from the pipe 26 to the pipe 25. As here shown, the valve comprises a casing having mounted therein a vertically movable valve stem 28 on which is mounted a 55 valve member 29 to control the port within the valve casing. A spring 30 acts on this valve to hold the same normally on its seat but is of such strength that it will yield to 60 permit the valve to open under the pressure of the liquid in the pipe 25. The stem 28, which is rigidly secured to the valve member 29, projects above the upper end of the casing and is arranged to be engaged by a 65 lever or operating handle 31 which is piv-

totally mounted on a bracket 32 carried by the valve casing.

The liquid in the plunger is preferably forced into the cylinder to actuate the plunger by introducing air under pressure into the upper end of the plunger. As here shown, an air pipe 33 is mounted on the upper head 17 of the plunger and communicates with the interior of the plunger. This pipe extends laterally from the plunger and its outer end 75 is divided to provide two branches, one an inlet branch 34 and the other an outlet branch 35. The inlet branch 34 is provided with a coupling member 36 whereby it may be connected with a flexible hose 37 leading to a 80 source of supply of air under pressure, such as an air compressor or a high pressure storage tank. A check valve 38 is interposed in the inlet branch 34 of the air line to prevent the reverse flow of the air. A manually operated valve 39 is interposed in the outlet branch of the air line to normally close the same.

When air under pressure is delivered to the 90 branch 34 of the air line this air will be introduced into the upper end of the plunger 11 and will force the liquid which is in the plunger out through the conduit, consisting of the pipes 22, 24, 25, 26 and the valve 27, which conduit will deliver the liquid into 95 the cylinder below the plunger, thereby forcing the plunger upward and lifting the load thereon. The valve 27 will operate to prevent the reverse flow of the liquid through the conduit and thereby retain the plunger 100 in the position to which it has been elevated. The valves in the air line being normally closed will prevent the escape of the air from the plunger and will also serve to retain the plunger in the position to which it has been elevated. In order to lower the plunger it is necessary, first, to relieve the air pressure within the plunger and to then manually operate the controlling valve 27 to permit the 105 reverse flow of the liquid through the conduit. Neither the air controlling devices nor the liquid controlling devices will, independently of the other, permit the lowering of the load. In this manner a very large factor of safety is provided because it is extremely 110 unlikely that both controlling devices will be inadvertently or accidentally operated. The controlling valve is normally closed against the reverse flow of liquid and must be held open by the operator in order to lower 115 the load. By manipulating the valve to regulate the flow of liquid therethrough the speed at which the load is lowered may be controlled.

In the lubrication of an automobile it is 120 customary to spray the springs with oil, compressed air being used for that purpose. In the present device, I have provided means whereby the air under pressure which has 125 been utilized to elevate the load may be used 130

for operating the oil spray, without lowering the load. To this end the air outlet pipe 35 is provided with a coupling 40 by means of which it may be connected with a flexible hose 41 leading to the oil spray. After the oil spray has been connected with the air line the valve 39 is opened and the air under pressure permitted to pass to the oil spray, thus utilizing air under pressure which would otherwise be wasted. The controlling valve 27 of the liquid conduit being closed the withdrawal of the air under pressure will have no effect upon the position of the plunger.

The runways 14 are provided with means 15 for supporting the same out of contact with the supporting surface and, in the present instance, the supporting means comprises transverse members 42 rigidly secured to the undersides of the runways, there being one of 20 these supporting members at each end of each runway. Each supporting member has its lateral lower portions cut away so as to provide the same with a narrow central part 43 which contacts with the supporting surface, 25 thereby spacing the lateral portions of the supporting members such a distance from the supporting surface that the foot of an operator will not be injured if it should be inadvertently placed in the path of the supporting member as the load is lowered. The runways are reinforced by means of truss rods 44 which extend over brackets 45, rigidly secured to the transverse frame member 13, and are rigidly secured at their ends to the respective supporting members 42.

Each runway is provided at each end thereof with an inclined portion or shoe 46 the outer end of which rests upon the supporting surface and serves to guide the wheels of 40 the vehicle onto the runway. This shoe is pivotally mounted on the end of the runway so that it will yield and cause no injury should it strike the foot of the operator or any other obstruction. As here shown, each shoe is 45 provided at each side thereof with an ear 47 rigidly secured thereto and having a slot 48 to receive a pin 49 projecting from the adjacent flange 15 of the runway. The lower portion of each ear is curved as shown at 50 and 50 is of such length that when the shoe is in its downwardly inclined position the curved end of the bracket will rest upon the upper surface of the supporting member 43, thus providing a firm support for the shoe and maintaining the inner edge thereof in line with the bottom of the runway. At the rear of the curved portion the ear is provided with a shoulder 51 and when the shoe has been moved to its elevated position, as shown in Fig. 7, 55 the curved portion of the ear will be moved past the supporting member 42 and the rear portion of the shoe will drop so as to bring the shoulder 51 into engagement with the outer edge of the supporting member, thereby 60 rigidly locking the shoe in an elevated posi-

tion, in which position it will serve as a stop to prevent the automobile from running off the runways.

If desired, the apparatus may be provided with a receptacle to receive oil drained from the crank case or other part of an automobile. In the present device a drain pan 52 is carried by an arm 53 pivotally mounted at 54 on the lower side of one of the runways so that it can be moved to various positions beneath the automobile. While I have shown but one such drain pan it will be obvious that a similar pan may be provided on the opposite side of the frame member 13.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. In an automobile lifting mechanism, comprising a lifting element mounted for vertical movement, means for actuating said lifting element, and a frame carried by said lifting element, runways mounted on said frame on opposite sides of said lifting element, each of said runways comprising an end portion pivotally mounted thereon for movement either into a downwardly inclined position or into an upwardly extending position, and means controlled by the movement of said portion of said runway to said upwardly extending position to lock the same in that position.

2. In an automobile lifting mechanism comprising a lifting element mounted for vertical movement, means for actuating said lifting element, and a frame carried by said lifting element; runways mounted on said frame on opposite sides of said lifting element, each of said runways having near one end thereof a supporting member, a shoe arranged at said end of each runway, a locking member carried by said shoe, means for pivotally and slidably connecting said locking member with said runway, said locking member being so arranged that when the outer end of said shoe is elevated said locking member will be moved into locking engagement with the outer edge of said supporting member to retain said shoe in its elevated position.

3. In an automobile lifting mechanism comprising a lifting element mounted for vertical movement, means for actuating said lifting element, and a frame carried by said lifting element; runways mounted on said frame on opposite sides of said lifting element, a supporting member secured to each of said runways near the end thereof, a shoe arranged at said end of said runway, ears secured to said shoe and having slots, pins carried by said runway and extending

through said slots, each of said ears having its lower portion arranged to rest upon said supporting member, and support said shoe in proper relation to said runway, when the 5 outer end of said shoe is in its lowermost position, said ears also having shoulders on their rear ends adapted to be moved into line with the outer edge of said supporting member when the outer end of said shoe is elevated 10 and thereby lock said shoe in its elevated position.

4. In an automobile lifting mechanism comprising a lifting element mounted for vertical movement, means for actuating said 15 lifting element, and a frame carried by said lifting element; runways mounted on said frame on opposite sides of said lifting element, each of said runways having a member connected with one end thereof for movement 20 into either a downwardly inclined position or an upwardly extending position, said runway and said member having cooperating parts arranged to be moved automatically into locking engagement one with the other 25 when said member is moved to said upwardly extending position.

5. In an automobile lifting mechanism comprising a lifting element mounted for vertical movement, means for actuating said 30 lifting element, and a frame carried by said lifting element; runways mounted on said frame on opposite sides of said lifting element, each of said runways having a member connected with one end thereof for movement 35 into either a downwardly inclined position or an upwardly extending position, said runway and said member having cooperating parts rigid therewith and so arranged that the movement of said member to said upwardly 40 extending position will cause said part of said member to move into locking engagement with said part of said runway.

6. In an automobile lifting mechanism comprising a lifting element mounted for 45 vertical movement and a runway carried by said lifting element, a member pivotally mounted at one end of said runway for movement into an upwardly extending position, and a part carried by said runway to retain 50 said member in said upwardly extending position, said member and said part being so arranged that they will be brought automatically into retaining relation when said member is moved to said upwardly extending 55 position.

In testimony whereof, I affix my signature hereto.

ION VON KERT HOTT.
